(57)

CLAIM

The ornamental design for a display screen with graphical user interface for an imaging protocol manager, as shown and described.

DESCRIPTION

The FIGURE is a front view of a display screen with graphical user interface for an imaging protocol manager. The stippling and grey shaded regions indicate a contrast in appearance. The outermost broken line showing of a display screen and the remaining broken lines illustrating text, symbols, and elements of the graphical user interface illustrate portions of the article, and form no part of the claimed design.
